SASH FASTENER

Albert Handfield, Montreal, Quebec, Canada

Application December 31, 1934, Serial No. 759,830
In Canada January 2, 1934

4 Claims. (Cl. 292—61)

The present invention pertains to a novel sash fastener, or a device for locking a sash to another sash or to a fixed member in a window of the sliding sash type.

5 The principal object of the invention is to provide such means accessible and operable only from the inside of the window, so that a partially opened window cannot be further opened from the outside to permit unauthorized entry 10 into the building. Another object is to provide such a device which is partly automatic in its operation.

More specifically, the invention embodies a locking pin slidably transversely in a movable 15 sash and adapted for locking engagement with another sash. The pin is rotatable as well as slidable and carries a cam adapted for co-operation with another cam fixed in the sash. By 20 means of a lever and chain, the pin may be rotated to effect a spreading of the cams and thereby a retraction of the locking pin from the other sash.

The turning mechanism involves a pair of ratchets, one of which winds a spring when 25 turned in the driving direction. Consequently, when the driving movement is stopped, the spring unwinds and turns one of the ratchets idly over the other. At the same time, the cam on the pin also turns, and another spring acting 30 on the locking pin, draws the two cams together and thereby projects the pin again into locking position.

The invention is fully disclosed by way of example in the following description and in the 35 accompanying drawing in which

Figure 1 is a vertical section through a pair of window sashes equipped according to the invention;

Figure 2 is a detail elevation corresponding to 40 Figure 1;

Figure 3 is a detail vertical section in a plane at right angles to Figure 1;

Figure 4 is a section on the line 4—4 of Fig. 3;

Figure 5 is a detail section in the same plane 45 as Figure 1, showing the device in released position;

Figure 6 is a similar section showing the device in locking position; and

Figure 7 is a detail plan section showing the 50 locking plate.

Reference to these views will now be made by use of like characters which are employed to designate corresponding parts throughout.

In Figure 1 are shown a pair of sashes 1 and 55 2 of a conventional sliding sash window. One

of the sashes, preferably the upper sash, is formed with an opening 3 drilled transversely through its frame. Into this opening is driven a tube 4 having prongs 5 struck outwardly therefrom so that the tube cannot be pulled out of the opening. 5

A locking pin or stem 6 is slidably mounted in the tube and carries near its outward end a fixed collar 7. Directly behind this collar, the stem is surrounded by a compressed spring 8 engaging 10 the collar and also the adjacent end of the tube 4.

The outer end of the tube 4 is beveled at 9, and adjacent thereto is a complementary beveled cam 10 formed integral with the stem 6. 15 The cam is also formed with a collar 11 having a ratchet 12 facing inwardly.

Adjacent to this member, another collar 13 is rotatably mounted on the inner end of the stem 6 and is formed with a ratchet face 14 adapted 20 to engage the aforementioned ratchet face 12. A lever 15 extends laterally from the collar 13 for operating purposes as will presently appear.

A compressed coil spring 16 surrounds the outer extremity of the stem 6 and bears against 25 the collar 13, tending to hold the ratchet faces in engagement with each other. This spring has one end secured to the member 6 and the other end to the collar 13. The adjacent end of the member 6 is flattened at 17 or keyed into 30 engagement with the end of collar 13 to prevent the parts from slipping off.

A cap 18 covers the parts exposed at the inner face of the sash 2 and is secured to the latter by suitable fastening devices 19, as shown more 35 clearly in Figures 2 and 3. The cap has a slot 20 through which a lever 15 projects and in which said lever is adapted to move. Finally, a chain or cable 21 hangs from the free end of the lever 15 and is of such length as to be easily reached regardless of the position of the sash 2. A vertical plate 22 is secured to the sash 1 directly opposite the outer end of the locking pin 6 and is formed with a vertical series of apertures 23 adapted to selectively receive the pin 6 and thereby determine 45 the vertical adjustment of the sash 2.

In the operation of the device, assuming that the sash 2 is locked as in Figures 1 and 6, the lock is released for a new adjustment by first pulling on the chain 21. The cam 10 obviously turns with 50 the two ratchets 12 and 14 controlled by the lever 15 and is retracted by reason of its rotation against the fixed beveled end 9 of tube 4, to the position shown in Figure 5. The locking pin 6, being integral with the cam 10, is retracted from the lock- 55

ing plate 22, as also shown in Figure 5, whereupon the sashes 1 and 2 may be readjusted relatively to each other.

The new adjustment is secured merely by pulling again on chain 21. The spring 16 having been wound by pulling the chain, has brought collar 13 to its former position. The sliding movement of the locking pin takes place under the action of the compressed spring 8 which expands from the position shown in Figure 5 to that shown in Figure 6 when the cam is permitted to approach the beveled face 9.

Although a specific embodiment of the invention has been illustrated and described, it will be understood that various alterations in the details of construction may be made without departing from the scope of the invention, as indicated by the appended claims.

What I claim is:—

- 20 1. A locking device for a window sash comprising, in a sash, a fixed cam member, a locking pin 20 slideable and rotatable therein and adapted to project therefrom, another cam member fixed to said pin and adapted to co-operate with the first cam member to slide said pin, a ratchet face formed on said second cam member, and another ratchet rotatable on said pin and adapted to engage said ratchet face and turn the second cam member.
- 25 2. A locking device for a window sash comprising, in a sash, a fixed cam member, a locking pin 25 slideable and rotatable therein and adapted to project therefrom, another cam member fixed to said pin and adapted to co-operate with the first cam member to slide said pin, a ratchet face formed on said second cam member, another ratchet rotatable on said pin and adapted to engage said ratchet face and turn the second cam member, a torsion spring secured to said ratchet and adapted to wind on turning said ratchet in the driving direction, whereby said ratchet turns idly 30 over said ratchet face when the driving movement is arrested, an operating lever extending from said ratchet, and a chain hanging from said lever.
- 30 3. A locking device for a window sash comprising, in a sash, a fixed cam member, a locking pin 30 slideable and rotatable therein and adapted to project therefrom, another cam member fixed to said pin and adapted to co-operate with the first cam member to slide said pin, a ratchet face formed on said second cam member, another ratchet rotatable on said pin and adapted to engage said ratchet face and turn the second cam member, an operating lever extending from said ratchet, and a chain hanging from said lever.
- 35 4. A locking device for a window sash comprising, in a sash, a fixed cam member, a locking pin 35 slideable and rotatable therein and adapted to project therefrom, another cam member fixed to said pin and adapted to co-operate with the first cam member to slide said pin, a ratchet face formed on said second cam member, another ratchet rotatable on said pin and adapted to engage said ratchet face and turn the second cam member, a torsion spring secured to said ratchet and adapted to wind on turning said ratchet in the driving direction, whereby said ratchet turns idly 40 over said ratchet face when the driving movement is arrested, an operating lever extending from said ratchet, and a chain hanging from said lever.

ALBERT HANDFIELD. 35
